F. E. BATES.

POWER CONTROL FOR SPINNING MACHINES.

APPLICATION FILED FEB. 1, 1911.

1,109,195.

Patented Sept. 1, 1914.

UNITED STATES PATENT OFFICE.

FRANK E. BATES, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

POWER CONTROL FOR SPINNING-MACHINES.

1,109,195.

Specification of Letters Patent.

Patented Sept. 1, 1914.

Application filed February 1, 1911. Serial No. 605,930.

To all whom it may concern:

Be it known that I, FRANK E. BATES, a citizen of the United States, residing at Whitinsville, Worcester county, Massachusetts, have invented certain new and useful Improvements in Power Control for Spinning-Machines, of which the following is a specification.

The invention is an improvement in power-controlling devices for spinning, twisting or like machines, the object being to provide a simple and effective belt-shipper or power-controlling mechanism which will safely and reliably maintain the power on or off as desired, so that vibration or the tendency of the driving belt to creep from the loose to the fast pulley, or vice versa, will be reliably prevented, but which will nevertheless be capable of easy operation by the attendant when such change is desired.

In the drawings forming part hereof, and comprising one sheet, Figure 1 is an end elevation of an ordinary spinning machine to which the invention is shown as applied; Fig. 2 is a side elevation of the end portion of such a machine with the lower deck-board of the creel in longitudinal section; Fig. 3 is an enlarged detail of the upright shipper shaft with parts broken out and other parts shown in section; Fig. 4 is a modified form of the detent mechanism; Figs. 5 and 6 are top plan and perspective views, respectively of the head flange which is provided with the upper detent members; Fig. 7 is a perspective view of the shipper shaft support upon which the lower detent mechanism is provided; and Fig. 8 is a detail in horizontal section on line 40 VIII—VIII of Fig. 3, of the shipper-shaft crank.

The spinning machine shown, and as will be recognized by those familiar with the subject, comprises the usual end frames 1 and longitudinal side beams 2 upon which the spindles, rollers and other operating parts of the machine are carried, and also a superstructure or creel 3 upon which the supply bobbins, not shown, are intended to be supported, the creel in the present case being a two-story creel, as shown in the drawings.

The power that drives the machine is imparted to it at one end by a driving belt, 45 which is adapted to run on either the fast

pulley 5 or the loose pulley 6, according as to whether it is desired to run or stop the machine, as will be well understood. The position of the belt is controlled by the belt-fork 7, carried on the end of a shipper rod 8, which is appropriately mounted in bearings so that it can slide lengthwise a sufficient distance to carry the fork and belt from one wheel to the other. The shipper rod is most conveniently disposed 60 beneath the lower deck-board of the creel as indicated in Fig. 2 except where it intersects the end frame 1 and extends substantially from one end of the machine to the other, so that it will be accessible for operation at different separated points along the length thereof; the distance which it is required to be moved in order to start or stop the machine will of course depend on the width of the fast and loose pulleys, and its 65 movement is preferably limited to an extent sufficient for this purpose. The means for moving the shipper rod in this manner comprises an upright rock-shaft 9 journaled in the creel superstructure and carrying, 70 preferably at its upper end, a pair of lever handles 10, by which it may be rotated on its vertical axis. The handles have a common hub which is securely fastened to the top of the shipper shaft 9, as by means of a 75 set-screw, and extend cross-wise of the machine, overhanging the creel-boards and then dropped or depressed, as shown in Fig. 1, so that they will be out of the way and yet be readily reached from either side of 80 the machine. The vertical shipper shaft also carries a laterally projecting head flange or shoulder-forming member 11 which may either be formed integrally with the hub of the hand-levers, as shown at 85 11^a in Fig. 4, or as a separate part attached thereto or to the shaft, as shown in Fig. 3. In the latter form, which is preferred in the present instance, because most readily adaptable to existing machines, the bottom of the hub of the handle lever is slotted and the flange member 11 is formed with 90 keys 12 on its upper side (Fig. 5), corresponding to the slots and adapted to interlock with the hub so that both will turn together and with the shaft, and also so that the weight of the vertical rock-shaft 9 will 95 be sustained against gravity by the flange member.

The journal means of the rock-shaft is 110

provided by a vertical tube 13, which is simply a section of piping used as an intermediate support for the decks of the creel. There may be several of these tubular supports along the length of the machine for the same purpose, and one or all of them may form also the support for a rock-shaft such as 9. Each pipe is threaded and provided with nuts 14 which clamp opposite sides of the lower creel-board, thereby producing a rigid form of mounting. The top of the supporting tube carries a cross-head or collar 15 fastened to it by means of a set-screw and occupying a position immediately beneath the head flange 11, of the handle lever hub and adapted to support the latter and the vertical shaft 9, and between these two parts a pair of complementary detent members is provided. In the specific instance taken for illustration, these detent members comprise one or more cavities 16 in the head-flange 11 and a round-headed removable stud 17 placed in one of the recesses in the cross-head or collar 15, the stud being adapted to enter the cavities when in registry therewith, and the arrangement of these members is such that the rotation of the shaft 9 is yieldingly prevented by the mutual engagement of the stud and one of the cavities, until sufficient force is brought to bear to cause the cavity to ride over the obstruction formed by the top of the stud. This action is necessarily accompanied by vertical movement of the rock-shaft in its supporting bearings, and considerable force is thus required to start the rock-shaft in its rotary movement, since its own weight and the pressure of other parts acting upon it must be overcome to disengage the detents.

The lower end of the rock-shaft carries a slotted crank-arm 18 which is engaged with a vertical stud 19 carried by a lateral arm 20 adjustably secured to the shipper-rod 8, above referred to, so that when the shaft is rotated the shipper rod 8 will be correspondingly shifted in its longitudinal bearings. The length of the stud 19, which is carried by the shipper rod, is sufficient to accommodate the vertical movement of the rock-shaft and crank-arm thereon, and such movement is limited by a cross-pin 21 and washer 22 to confine the arm upon the stud and prevent accidental disengagement, but it is within this invention to connect the shipper shaft to the shipper rod without such provision for movement and to rely on the flexibility of the rod to accommodate and limit the vertical movement of the shipper shaft. Between the bottom of the tubular support 13 and the hub of the crank 18, as connected in the case illustrated, a spring 23 is interposed to force the rock-shaft downwardly and thereby supplement the effect of gravity in urging the detent members toward each other. A very effective en-

gagement between these members is thus provided without increasing the depth of penetration of the detent stud into its registering cavity or the shape or slope of the walls of the edges of the latter.

The head flange 11 preferably contains a plurality of cavities 16, as shown in Fig. 5, which adapt it for use on machines driven by belts of different widths, and also provides for intermediate positions of the power control, such as slow or half speed; but it will be understood that two of these cavities will ordinarily be sufficient to define positive off and on positions of the belt fork. The support 15 also has two recesses for accommodating the detent stud 17, and the latter may be placed in either one of these recesses, as desired, to be changed from one to the other when required, as, for instance, when a portion of the under surface of the head-flange has become worn by the friction of continual movement over the stud.

It will be obvious from the description above given that when the power has been turned off by the operation of the handle levers, it will be safely maintained off against all ordinary influences which might throw it on, such, for instance, as a creeping belt or vibration or accidental contact with the shipper fork (in cases where the power is controlled by the slipping of a belt), and similarly, when the power has been turned on, the position of the parts will be equally or sufficiently maintained against reverse movement. It will be noted further, that the vertical separability of the detent mechanism above explained is specially adapted to the position of the handles on the top of the vertical shipper shaft and above the creel, where they are generally somewhat above the shoulders of the attendant, because thereby the force required to move them will ordinarily be exerted partly in an upward direction which will facilitate the disengagement of the detents while yet permitting their normal engagement to be very positive and safe.

I claim:

1. In a power-driven machine, a vertical rock-shaft, a handle thereon, a power-controlling device connected with the rock-shaft and movable in one direction or the other to throw the power on or off according to the direction in which the shaft is turned, in combination with a flange on said rock-shaft, a fixed collar beneath said flange, and a detent operative between said flange and collar to hold the rock-shaft in determinate on and off positions and adapted to cam the flange and shaft upward against the force of gravity when force is applied to the handle to rotate the shaft.

2. Power-controlling mechanism comprising the combination of a support, a vertical rock-shaft journaled therein and pro-

vided with a handle, a power-controlling device connected with said rock-shaft, a flange on the said shaft, a fixed collar on the support immediately beneath said flange, the 5 two last-recited elements being provided in their meeting faces, one with a plurality of recesses and the other with a series of rounded cavities, and a rounded head stud adapted to be seated in any of said recesses and to

engage said cavities with its rounded head 10 according as the shaft is turned.

In testimony whereof, I have signed this specification in the presence of two witnesses.

FRANK E. BATES.
